JOSEPH WARD, OF NEW YORK, N. Y.

Letters Patent No. 60,972, dated January 1, 1867.

IMPROVEMENT IN HOLLOW AUGERS.

The Schedule referred to in these Letters Patent and making part of the same.

TO ALL WHOM IT MAY CONCERN:

Be it known that I, JOSEPH WARD, of the city, county, and State of New York, have invented a new and improved Hollow Auger; and I do hereby declare that the following is a full, clear, and exact description thereof, which will enable others skilled in the art to make and use the same, reference being had to the accompanying drawings, forming part of this specification, in which—

Figure 1 is a longitudinal section of my invention, taken in the line *xx*, fig. 4.

Figure 2, a side view of the same.

Figure 3, a transverse section of the same, taken in the line *yy*, fig. 1.

Figure 4, a front or face view of the same.

Similar letters of reference indicate like parts.

This invention relates to a new and improved hollow auger for cutting tenons on the ends of spokes; and also on the ends of tool handles to receive the ferrules, the holes in the handles to receive the tang of the tool being bored at the same time. The object of the invention is to obtain an implement for the purpose specified which will be capable of being adapted to cut tenons of different diameters, as may be required.

A represents a cylindrical shell or case, one end of which is provided with a central projecting screw, *ax*, by which the tool is secured to a rotary mandrel of a lathe or to a bit-stock. This shell or case *A* is provided internally with guides *a*, in which the cutter-stocks *B* are fitted and allowed to slide freely towards and from the centre of the shell. The guides *a* have not a radial position in the shell, but a position tangential with a bit, *C*, inserted centrally in the shell. (See fig. 4.) *D* represents the cutters, which are secured by set-screws *b* on the front ends of the stocks *B*, and the latter are formed or provided with longitudinal throats *c*, extending entirely through them for the escape of the shavings. Three cutter-stocks, *B*, are shown in the drawings, but more or less may be used; two would answer for small augers designed to be turned by hand. The cutter-stocks are moved or adjusted within the shell or case *A*, as follows: Within the shell or case there is placed a cam, *E*, provided with three eccentric curved surfaces, *d*, each provided with two longitudinal slots, *e e*, through which screws *f* pass into the cutter-stocks, the heads of the screws being greater in diameter than the width of the slots *e*, as shown clearly in fig. 1. The cam *E* is retained in position within the shell or case *A* by means of screws *g*, which pass through slots *h*, made circumferentially in the shell, the heads of the screws *g* being greater in diameter than the width of the slots *h*.

From the above description it will be seen that by turning the cam *E* the cutter-stocks *B*, and consequently the cutters *D*, may be adjusted nearer to or further from the centre of the shell or case, and tenons cut of greater or less diameter, as may be desired. The cam *E*, after being adjusted to set the cutter-stocks or cutters, is retained in position by screwing up the screws *g*. The sides of the guides *a* are slotted longitudinally, and have screws *i* passing through them into the cutter-stocks *B*. These screws serve as guides for the cutter-stocks, as will be understood by referring to fig. 3. In cutting tenons on spokes for wheels the bit *C* is detached, but in cutting tenons on tool handles to receive the ferrules the bit is used to bore the handle to receive the tang or shank of the tool at the same time the tenon is being cut. The shell or case *A* is made with suitable openings, *j*, to admit of all the screws being accessible, so that they may be screwed up and relaxed as necessity may require.

Having thus described my invention, I claim as new, and desire to secure by Letters Patent—

1. The arrangement within the case *A* of the cutter-stocks *B*, constructed with discharge throats *C*, and adapted for adjustment by means of the cam *E* and guides *a*, as and for the purpose specified.
2. I claim the within-described tool adapted for cutting tenons and boring holes simultaneously, constructed and operating in the manner and for the purpose specified.

JOSEPH WARD.
